UNITED STATES PATENT OFFICE.

COPELAND TOWNSEND, OF NEW YORK, N. Y.

COMBINED ROTARY PUMP AND MOTOR.

1,338,265.

Specification of Letters Patent. Patented Apr. 27, 1920.

Application filed August 10, 1918. Serial No. 248,233.

To all whom it may concern:

Be it known that I, COPELAND TOWNSEND, a citizen of the United States, residing at New York, in the county of New York and State of New York, have invented certain new and useful Improvements in Combined Rotary Pumps and Motors, of which the following is a specification.

My invention relates to a combination rotary pump and motor, which can pump large volumes of water if power is supplied thereto, and which can be operated in the reverse manner to supply power if water or other liquid under pressure is supplied thereto. 10 The object of my invention is to devise a very compact and powerful pump or motor of the rotary type, which shall be smooth running, noiseless, free from vibration and subject to little wear and tear. 15 Other objects of my invention are a special combination of parts which supply a large and continuous flow of liquid, and other features which will be disclosed in the following description and drawings, which 20 illustrate a preferred embodiment of my invention. 25

Figure 1 is a perspective view of the device embodying my invention.

Fig. 2 is a section taken along the horizontal diameter thereof.

Fig. 3 is a section taken along the vertical diameter thereof.

Fig. 4 is an inside view showing the outer and inner plates.

Fig. 5 is a face view of one-half of an outer plate.

Fig. 6 is an inner view, partially in section, illustrating the inner ring and other details of the pumping mechanism.

Fig. 7 is a horizontal central section on one of the horizontal fins shown in Fig. 6.

Fig. 8 is a detail view, partially in section, showing a fin and its packing.

Fig. 9 is an inner view of the casing showing the ports therein.

Fig. 10 is a face view of one-half of an inner plate.

The device embodies a casing made of two like halves 5, having flanges 130, which 50 are connected by means of bolts 91. The casing has feet which are securely connected to a suitable base plate 84, which is suitably secured so that any vibration is minimized.

At the center thereof the casing 5 is provided with a packing box, 90, through which a shaft 9 projects into the interior of the

casing. If the shaft 9 is revolved by some suitable source of power, which is not shown in the drawings, then fluid under pressure is supplied by the device which now acts as 60 a pump and if fluid under pressure is led through the device in the reverse direction then the device acts as a motor and rotates the shaft 9.

As can be best seen in Fig. 3, the shaft 9 65 has an interior tapered portion 92, having a threaded end which co-acts with a nut 94. This nut 94 has a reduced neck 320 which bears against the adjacent inner plate 8, so that any axial play of the shaft is prevented. The shaft 9 has a hub 22 keyed thereto, and the inner plates 8 are secured to this hub 22 by means of screws 23.

As can be seen in Figs. 4 and 6, each plate 8 has a number of circular openings, 18 75 therein, into which a series of brackets 16, project, so that the brackets 16 rest in these circular openings. These brackets 16 have radial arms 20 connected to arcuate shoes or claws 43, which contact with the exterior 80 periphery of an interior floating ring 70. It is preferred to have the shoes 43 merely possess a certain amount of frictional contact with the floating ring 70 although, if desired, some positive connection of any 85 well-known kind could be used so as to insure the simultaneous rotation of the shoes 43 and floating ring 70.

As shown especially in Fig. 3, there is an inner plate 8 around each side of the floating ring 70, and these inner plates 8 are secured by any suitable means to an intermediate ring 170. The brackets 16 are connected at each end to exterior plates 4 by means of rivets 16' or any other suitable means. The 90 exterior plates 4 fit upon the interior plates 8 in a fluid tight manner, and can be moved radially, independently of the inner plates 8. The outer plates 4 have an exterior ring 2 secured at their ends by means of screws 3 100 or other suitable means, and the ring 2 fits tightly into a guide ring 1 which is connected to rod 80 connected to link 81 pivoted at 82 and having a hand hold 83 whereby the link 81 can be moved up and down, and move guide ring 1 and the exterior ring 2 and the brackets 16 so that they are either concentric with respect to the shaft 9, or can be made eccentric with respect thereto to any extent enabled by the size of the 110 apparatus.

As can be seen especially in Figs. 6, 7 and

8, the hub 22 has a series of radial grooves therein, which are in line with a corresponding series of grooves, 40, in plates 8, and fins 41, which are connected to the inner floating ring 70 by means of cylindrical packings 42, project into these alined grooves. The cylindrical packings 42 extend through the entire space between rings 8, and the branches of the fins 41 on opposite sides of 10 the said cylindrical packings have a certain amount of tangential play, so that if the plates 8 and the floating ring 70 are rotated simultaneously there is a certain amount of give or play between them, and they are not 15 rigidly connected together.

As the materials used ordinarily for packings of this kind have a certain amount of resilience, this is sufficient to allow for a certain yield between the fins and their 20 packings 42.

Hence when the shaft 9 is rotated, the hub 22 and the inner plates 8 as well as the intermediate ring 70 are simultaneously rotated therewith. The brackets 16 may 25 be placed in any desired eccentric position by suitably shifting the outer plates 4 by means of the link 81. If the brackets 16 are placed in the eccentric position shown in the drawings, then the inner floating ring 30 70 also assumes an eccentric position. The rotation of the plates 8 causes the rotation of the brackets 16 and the shoes 43, and the shoes 43 cause the rotation of floating ring 70 about a center below the common center 35 of ring 170 and hub 22, so that the inner floating ring will have a relative up and down motion combined with the rotation thereof. Hence, as shown especially in Fig. 6, the upper and lower halves of fins 40 41 will move inwardly and outwardly in their grooves, and the chambers or inclosed spaces formed by two adjacent fins 41 and the intermediate opposite peripheries of intermediate ring 170 and the floating ring 45 70, will be greater in volume at the upper end of the apparatus than at the lower end. Conversely, the chambers formed by adjacent inner branches of the fins 41, and the intermediate opposite peripheries of 50 floating ring 70 and the hub 22, will be least in volume where the first mentioned chambers or inclosed spaces are greatest and will be greatest in volume where the first mentioned chambers are smallest.

55 The direction of rotation may be clockwise in the view shown in Fig. 6.

As shown in Fig. 1, the casing is provided with pipes 100 and 101, either one of which may be the entrance pipe, or the 60 discharge pipe of the device, dependent upon the direction of eccentricity of the floating ring.

The pipe, 100, as shown in Fig. 1, is connected to two pipes 33, which are connected with glands 32 in the casing. The

65 pipes 33, as shown especially in Figs. 2 and 9, communicate on the one side with outer annular ports 301 and 301', and inner annular ports 300 and 300'. As seen especially in Fig. 9, partitions 50 and 50' are 70 provided which extend from one side of the casing to the other, so that the casing is divided into two spaces, one of which is in communication with the exterior port 301 and the interior port 300' and the other 75 of which is in communication with the exterior port 301' and the interior port 300.

80 As can be seen especially in Figs. 4 and 5, the outer plates 4 are provided with a series of outer ports 35 and inner ports 35' which are adapted to come into communication with the outer and inner ports of the casing respectively.

85 As is shown especially in Fig. 10, the inner plates 8 are provided with a series of outer ports 15 and inner ports 15' which are adapted to communicate with the ports 35 and 35' of the outer plates 4.

90 The parts are secured together by attachments of the ordinary kind.

95 Thus holes 23' are provided in plate 8 for members 23. As can be seen in Fig. 5 holes 113 are provided for screws 3. The plates 8 are secured to the ring 170 by means of bolts passing through holes 25.

100 As can be seen particularly in Fig. 6, a guide 102 is provided for the ring 1.

105 As can be seen particularly in Fig. 3, packing 90 is provided with the usual follower bolts 191. The operation of my device is as follows: Let us suppose that water or other fluid, either liquid or aéri-form is admitted to the pipe 100. It passes through the two pipes 33 on either side of the casing and then enters the casing at both sides thereof through the annular ports 301 which because of the partitions 50 and 51 communicate with the ports 300' only. The fluid then passes through those ports 35 and 35' in the plates 4, and those ports 15 and 15' in the plate 8 which at that time are in communication with the ports 301 and 300'. The fluid therefore enters between the hub 22 and the inner floating ring 70, and between the intermediate ring 170 and the floating ring 70, and is confined between these rings.

110 As can be seen particularly in Fig. 6, if the center of the floating ring 70 is pushed below the shaft 9 then the chambers formed by the fins 41 and the rings 170 and 70 are largest at the upper part of the apparatus, and the chambers between the hub and the floating ring 70 are largest at the lower part of the apparatus.

115 When the shaft 9 is rotated in a clockwise direction, the hub 22, plate 8, ring 170, brackets 16 and floating ring 70 also rotate therewith, as well as plates 4 and ring 2.

Since as can be seen particularly in Figs. 6, 7 and 8, the floating ring 70 passes through the fins 41, and since the fins 41 are provided with the elastic cylindrical packings 42 which make a fluid tight connection with the ring 70, the fins 41 are moved in the grooves 40 to and from the center of the shaft 9, so that as seen especially in Fig. 6, the chambers between the floating ring 70 and the intermediate ring 170 decrease in size as the shaft is rotated and then again increase in size. The same is true of those chambers between the hub 22 and the floating ring 70. As a result the fluid which has been drawn in through the ports 301 and 300' is powerfully expelled through the ports 300 and 301'. These chambers, which may be called discoidal chambers for convenience, alternately increase and decrease in volume, sucking in liquid as they increase in volume and discharging it as they decrease in volume. The pipe 101 can be made the entrance pipe if desired by simply reversing the direction and eccentricity of the ring 70 and the apparatus could be used as a motor by forcing in liquid or an aeriform fluid under pressure. Any desired force within large limits can be secured by operating the hand hold 83 since it will be obvious that if the ring 70 is made concentric with the shaft 9 that the pumping effect will be zero.

An important feature of my invention is making the openings in the fins 41 larger than the thickness or lateral dimension of the ring 70 and filling up this space in the fins 41 by means of the cylindrical packings 42 whereby the fins and the ring have a certain amount of relative angular movement with respect to each other for inequalities in the apparatus, and for the eccentricity of ring 70. The fins may be swiveled in the packings for this purpose, to allow a limited angular movement.

I have described a preferred embodiment of my invention but it is clear that numerous changes and omissions can be made in the details thereof without departing from its spirit.

This application embodies the invention of my former application, Serial No. 718,171, filed Sept. 3, 1912, as well as improvements thereon.

I claim:

1. In combination, a plurality of spaced ring-like rotatable members, means for simultaneously rotating them together, means located at the sides of said ring like members for preventing the escape of fluid forced in between them, fins separating the annular spaces between the said ring like members into a plurality of discoidal chambers, means for causing these discoidal chambers to increase in volume during one part of the rotation of the said members,

and for causing the said discoidal chambers to decrease in volume during another part of the said rotation, and means for conducting fluid to and from the said discoidal chambers, and means for moving one of said ring-like members so that the centers of said ring-like members occupy different relative positions and for holding them in said positions during their rotation. 70

2. In combination, a plurality of spaced ring-like rotatable members, means for simultaneously rotating them together, means located at the sides of said ring-like members for preventing the escape of fluid forced in between them, fins separating the annular spaces between the said ring-like members into a plurality of discoidal chambers, means for causing these discoidal chambers to increase in volume during one part of the rotation of the said members, and for causing the said discoidal chambers to decrease in volume during another part of the said rotation, and means for conducting fluid to and from the said discoidal chambers, said fins having a radial movement with respect 85 to the said ring-like members, and means for moving one of said ring-like members so that the centers of said ring-like members occupy different relative positions and for holding them in said positions during their 90 rotation. 95

3. In combination, a plurality of ring-like members one of which is movable relative to the others, so that its center can occupy different relative positions, means for shifting said movable ring-like member so that it is eccentric with respect to the other and is held in the said eccentric position, means for simultaneously rotating said ring-like members while they are in the said relative 100 eccentric position, means located at the sides of the ring-like members for preventing the escape of fluid introduced into the annular spaces between them, fins secured in a fluid tight manner to one of said ring-like members and capable of radial movement, the said fins dividing the said annular spaces between the said ring-like members into a plurality of discoidal chambers, and means 105 for simultaneously rotating the said ring-like members so that the said fins are moved to and fro during the said rotation and the said discoidal chambers alternately increase and decrease in volume during the said rotation, and means for conducting fluid to 110 and from the said discoidal chambers at desired points of the said rotational path. 115

4. In combination, three ring-like members, the innermost and outermost of said ring-like members being concentric and the intermediate member being eccentric with respect to the other two, means for simultaneously rotating the three said ring-like members, means located at the sides of said ring like members for preventing the lateral 125 130

escape of fluid located in the two annular spaces between them, the said intermediate ring-like member being connected to fins which separate the two said annular spaces 5 into discoidal chambers, the rotation of the said intermediate member causing a radial movement of the said fins, whereby the said discoidal chambers alternately increase and decrease in volume, the discoidal chambers 10 in one of said annular spaces increasing in volume while the adjacent discoidal chambers in the other of said annular spaces decrease in volume, and means for conducting fluid to and from the said discoidal chambers 15 at predetermined points.

5. In combination, a rotatable shaft carrying a hub, a series of radial grooves in the said hub, disk like plates secured to the said hub at both sides thereof, a ring secured to the said plates and forming a fluid-tight annular space with respect to them and the said hub, the said plate having a series of radial grooves in line with the grooves in the said hub, a series of perforations in the said plate, brackets having radial arms resting in the said perforations, the said arms having arcuate shoes, a floating ring held between these shoes and between the said hub and the said first mentioned ring, means for holding the said brackets and shoes concentric or eccentric with respect to the center of the said shaft, so that the said floating ring can be held concentric or eccentric to the said shaft, fins located in the said grooves in the hub and in said plates and secured to the said intermediate ring in a water tight manner, the said fins having a limited angular movement with respect to the said floating ring, means for 40 preventing the lateral escape of fluid between the said floating ring and the said first mentioned ring, and means for conducting fluid to and from the discoidal chambers formed between the hub and the said rings by the said 45 fins, whereby, when the said hub is rotated the said three rings are simultaneously rotated therewith and the eccentric rotation of the said floating ring causes a radial movement of the said fins so that the said discoidal 50 chambers alternately increase and decrease in volume, the chambers on one side of the floating ring increasing in volume while the adjacent chambers on the other side of said floating ring simultaneously decrease in 55 volume.

6. In combination, a rotatable shaft carrying a hub, disk-like plates secured to said hub on each side thereof, a ring secured to the peripheries of said disk like plates and 60 concentric with the said hub and shaft, the said disk like plates having a series of perforations concentric with the said hub and equally spaced therefrom, brackets located in the said perforations and having radial

arms carrying arcuate shoes, a floating ring 65 carried between these shoes and located between the said hub and the first mentioned ring, centrally perforated plates exterior to said disk like plates and freely movable with respect thereto in all directions and 70 making a fluid tight connection therewith, the said centrally perforated plates extending beyond the said first mentioned ring and preventing the lateral escape of fluid intermediate the said floating ring and the 75 said first mentioned ring through the perforations in the said disk like plates, the said brackets being secured to the said centrally perforated plates, and means for shifting said centrally perforated plates so 80 that they can be made concentric or eccentric with respect to the said hub, whereby the said floating ring is also held either concentric or eccentric with respect to the hub, the said hub and disk like plates having a 85 series of aligned radial grooves, fins fitting into the said grooves and capable of movement therein and connected in a fluid tight manner to the said floating ring so that they 90 form a series of discoidal chambers on both sides of said floating ring, and means for conducting fluid to and from the said discoidal chambers.

7. In combination, a fin having a cylindrical packing intermediate the ends thereof, the said packing having an opening through which a ring can be passed and fitting tightly on both sides of said ring, the said fin having an angular movement with respect to the said ring. 95

8. In combination, a rotatable shaft having a cylindrical hub connected thereto so as to rotate therewith, disk-like plates of equal diameter secured to said hub on both lateral faces thereof and extending above 100 and below said shaft, the said disk-like plates being concentric with said hub, the said disk-like plates having a series of circular perforations of equal diameter and concentric with said hub located therein on 105 all sides of said shaft, outer plates located exteriorly to said disk-like plates and making a fluid tight connection therewith, said outer plates being of greater diameter than said inner plates and always projecting beyond them, an outer ring secured at the periphery of said outer plates, a guide-ring inclosing said outer-ring, a vertical rod secured to said guide ring, means for moving 110 said guide-ring up and down, guides for guiding said guide-ring so that it can only move up and down, an intermediate ring secured at the periphery of said disk-like plates and fitting fluid-tight against said exterior plates, which close the said perforations in said disk-like plates, brackets parallel to said shaft and secured to said outer plates and passing through said perfora- 115 120 125

tions, said brackets carrying radial arms having arcuate shoes of equal curvature, a floating ring held intermediate said shoes, the said hub and said disk-like plates having a series of alined radial grooves, fins mounted in said grooves and capable of radial movement therein, the said fins having perforations provided with a packing on each side thereof through which said floating ring passes, the said fins dividing the annular spaces between said hub and said floating ring and between said floating ring and said intermediate ring into a series of adjacent discoidal chambers, whereby, when 10 said hub is revolved, the said discoidal chambers alternately increase and decrease in volume, and ports for supplying fluid to said discoidal chambers as they increase in

volume, and for permitting the ejection of said fluid as they decrease in volume. 20

9. In combination, three ring-like members, means for simultaneously rotating them, means for giving the central ring-like member a radial movement while it is rotating, a plurality of fins connected to said central ring-like member and dividing the annular space between said ring-like members into discoidal chambers, said fins being capable of a radial movement, means for preventing the escape of fluid from the sides of the said ring-like members, and means for conducting a fluid to and from the said discoidal chambers. 25 30

In testimony whereof I hereunto affix my signature.

COPELAND TOWNSEND.
